(57) **CLAIM**

The ornamental design for a tire, as shown and described.

DESCRIPTION

FIG. 1 is a first perspective view of a section of the tire; FIG. 2 is a second perspective view of the section shown in FIG. 1;

FIG. 3 is a third perspective view of the section shown in FIG. 1;

FIG. 4 is an end view of the section shown in FIG. 1; and, FIG. 5 is a top view of the section shown in FIG. 1.

Dash-dash broken lines in the drawings are for illustrative purposes only; the dash-dash broken lines form no part of the claimed design. Dash-dot-dash broken lines in the drawings identify boundaries between the claimed design and parts of the tire that are not parts of the claimed design.
